UNITED STATES PATENT OFFICE.

GEORGE DOLEMBO AND GEORGE H. LAMBERT, OF MADISON, WISCONSIN.

INTERNAL-COMBUSTION ENGINE.

1,123,258.

Specification of Letters Patent.

Patented Jan. 5, 1915.

Application filed March 19, 1914. Serial No. 825,881.

To all whom it may concern:

Be it known that we, GEORGE DOLEMBO and GEORGE HENRY LAMBERT, citizens of the United States, residing at Madison, in the county of Dane and State of Wisconsin, have invented certain new and useful Improvements in Internal-Combustion Engines, of which the following is a specification.

10 Our invention relates to internal combustion engines, but more particularly to the means for admitting, firing, and discharging of the explosive mixtures, in a manner that will preclude the depositing of carbon in localities which are dangerous to the operation of engines of that class.

We attain these objects by the mechanism illustrated in the accompanying drawings in which—

20 Figure 1, is a side elevation partly in section, Fig. 2, is a front elevation, assuming that the engine is of the vertical type.

Similar numerals refer to similar parts throughout the several views.

25 1, is a crank case of usual type with two side plates carrying central integral bearings, in which the main shaft is revolvably disposed. The top of said case forms a circular flange or socket into which the lower 30 end of the cylinder, 2, is secured by screw threads or otherwise. On the top and outside of the said cylinder is disposed the valve chest 3, comprising a central socket adapted to surround and cover the cylinder, 35 a passage extending in opposite directions from the center of the cylinder and terminating in the side walls, into which the spark plugs 7, are disposed. A distance above the top of the cylinder the said passage is divided by a wall forming a second 40 passage or valve chamber.

At the extreme outer ends of the central wall and top plate of the second passage are two circular apertures in both plates, and into which are secured the intake valve cages 5.

On the rear side of the upper chamber, interjacent the valve cages is the intake pipe 4, which leads to and connects with the carbureter.

Adjacent the socket and under the exhaust valves 8, extending oppositely from the cylinder are the exhaust ports or pipes 34, forming one integral casting with the aforesaid chambers and intake pipe 4.

The valve cage 5, comprises a circular top

plate extending a distance beyond the threaded portion on the top of the valve chest, a gasket being placed between the two, a central hub and four posts extending downward to the valve seat, the arm 33, disposed on top and extending upward and outward from the edge of said cage, the whole to be one casting.

Within a slot in the top of the arm 33, is pivotally disposed lever 13, and secured to the same by the pin 25, the lever extending inward to the valve stem 6, through which a pin is disposed. Between the said lever and the top of the cage surrounding the pin is operatively mounted a spring 27, for holding the said valve 6, to its seat on the bottom plate of the said cage 5. The outer end of the lever 13, is pivotally connected to rod 14, by pin 26, the said rod extending downward to and passing through guide 36, to a cam 23, on cam shaft 24, the said cam 23, being timed to the requirements of the engine.

On the side of the crank case is disposed 80 a cam shaft or gear case 17. On the top of said case is disposed guides 35 and 36. Within the said case is disposed a cam shaft 24, journaled in each end of the case. Intermediate the ends of said shaft is disposed a 85 spiral gear 15, and on each side of said gear is mounted two cams 23, adapted to engage and operate the four cam rods 11 and 14, connected to the double set of intake valves 6, and exhaust valves 8, of the engine. 90

The exhaust valves 8, are disposed in vertical alignment under the intake valves 6, and seated in the lower wall of the valve chest 3, and retained in proper position by the sleeves 31. Under and abutting said sleeves are the collars 37, contiguous said collars 37, and surrounding the stem of valve 8, are mounted the springs 30. Abutting the lower ends of said springs is a washer slidably disposed on said stem and 100 retained in adjustment by the nut 9. The said nut engages and is in operative connection with the inner end of lever 10, which lever is pivotally connected to standard 12, by pin 29, and is also operatively 105 connected to cam rod 11, by the pin 28.

Within the crank case 1, is disposed the main shaft 18, to which are secured the two crank disks 19, spaced a distance apart and connected by the wrist pin 20. On said 110 wrist pin is disposed the connecting rod 21, which at its upper end is secured in op-

erative relation to the piston head 22, by the pin 32. On the said shaft 18, within the cam case 17, is a second spiral gear 16, meshing with the said gear 15, in proper ratio to operate the said cam rods 11 and 14, and move the valves as a double set simultaneously, to run the engine as a four cycle machine.

The spark plugs 7, being disposed at opposite ends of the combustion chamber and the explosive forces meeting over the cylinder it is evident that all carbon will be forced to the center of the chamber and the exhaust occurring at the ends of the chamber will sweep it back and out of the exhaust ports, it being well known that the most annoying deposits of carbon are opposite the spark plugs.

Having thus fully described our invention what we claim as new and our own and desire to protect by the grant of Letters Patent is—

In an internal combustion engine comprising a crank case, a main shaft, two crank disks, a crank pin connecting the disks, a connecting rod connecting the crank pin to a wrist pin, a wrist pin within a piston, a piston within a cylinder, a cylinder, a

valve chest adapted to cover the top of the cylinder, said valve chest divided to form two parallel chambers, two intake valves openings through the intermediate wall of said chest, two exhaust valves in the lower wall of said chest, two spark plugs at the ends of the lower chamber of said chest, a cam case on the side of the crank case, a cam shaft journaled within said cam case, four cams mounted on said shaft, a spiral gear mounted on said shaft, a second spiral gear mounted on the main shaft and meshing with the first gear, four cam rods, four rollers, one in the lower end of each of the said cam rods and coöperating with the cams aforesaid, four levers operatively connecting the four cam rods to the four valves as described and set forth.

In testimony whereof we affix our signatures in the presence of subscribing witnesses.

GEORGE DOLEMBO.
GEORGE H. LAMBERT.
